CORNELIS ZULVER, OF LONDON, ENGLAND, AND GERARD JOHAN LUGT, OF AMSTERDAM, NETHERLANDS.

CYLINDER HEAD FOR INTERNAL-COMBUSTION ENGINES.

Application filed October 23, 1924, Serial No. 745,292, and in the Netherlands August 27, 1924.

The cylinder head for an internal combustion engine, more especially for a Diesel engine is very difficult to design and make in such a manner that defects do not eventually develop. The object of our present invention is to produce a cylinder head which is so constructed as to be completely and permanently reliable.

In accordance with our invention, the cylinder head substantially comprises an annular part, the central aperture in which has a smaller diameter than has the cylinder, and of a central member equipped with the distributing means—such as valves, for supplying the fuel and the air and for discharging the combustion gases.

The valve, or set of valves, has to perform two functions, viz. the introduction of air and the discharge of the spent gases. The passages and ducts for the inlet of air and for the outlet of gases are preferably arranged in the annular part, so that the dimensions of the central member can be kept small. As the valves have to control both the inlet of air and the discharge of hot gases, an additional device is necessary for alternately closing the passages for these fluids. In accordance with our invention, this additional device may be an annular rotary valve disposed intermediate the annular part and the central member of the cylinder head.

In a preferred embodiment of our invention a plurality of valves are provided around the fuel supplying device, arranged to act in parallel, while the annular rotary valve has as many sets of ports as there are valves and valve chambers.

The arrangement of the distributing valves in a separate member has the advantage that this member is better adapted for expansion and contraction, that it is more elastic with respect to external forces and that it can be more easily tested with a view to ascertaining the presence of faults of the material than an integral cylinder head, while the stresses produced in casting in the central member and in the annular part are likely to be smaller.

The distribution of the required area for the passage of air and gases over two or more equivalent valves of relatively small dimensions decreases the liability of troubles during operation, because the complication caused by the increased number of

valves, valve springs, etc., is amply compensated for by the fact that the comparatively small valves will keep tight and will not become overheated. The serious danger of overheating of the valves is less likely since the valves control the inlet as well as the outlet.

The controlling device, i. e. the annular rotary valve, required in connection with double acting valves, is disposed at a considerable distance from the combustion space and is not subjected to high pressures. Furthermore, it may for the greater part be in contact with water cooled metallic surfaces, in addition to being cooled by the fresh air. Consequently this rotary valve does not impair the reliability of the whole mechanism. Owing to the provision of a comparatively large number of valves (e. g. six), acting in parallel, and of a corresponding number of ports adapted to be put in communication by the rotary valve with the passages in the annular part of the cylinder head, the said rotary valve has only to move through a small angular distance during the cycle in the cylinder.

In the annexed drawing showing by way of example only one embodiment of our invention,

Fig. 1 is a central vertical sectional view of a cylinder head constructed in accordance with our invention.

Figs. 1^a and 1^b are sectional views of parts of modified cylinder heads,

Fig. 2 is a horizontal section along the line II—II in Fig. 1,

Fig. 3 is a diagrammatic elevation of part of the rotary valve and the valve chambers while

Figs. 3^a and 3^b show two other positions of the last-mentioned parts relative to each other.

Integral with the cylinder wall 4 is the annular part 5 of the cylinder head. Said part 5 is supported by the jacket 6 and provided with an air inlet port 7 in communication with an annular passage 8, and with an outlet port 9 in communication with an annular passage 10 into which the combustion gases are discharged. The part 5 is provided with passages 11 for the circulation of cooling water. The central aperture in the annular part 5 is closed by a member 12, which is provided with six valves 13 and with a central fuel supplying device 14, the

details of which have not been shown. The six valves 13 are adapted to be simultaneously opened and closed by means of an actuating ring 15. The other actuating mechanism has not been illustrated, because it does not form part of the invention. The valve chambers 16 have rectangular ports in the outer wall of member 12, and their walls are cooled by water circulating 10 through passages 17.

Disposed between the part 5 and the member 12 is the annular rotary valve 18, a cover 19 serving to retain the central member 12 and the annular valve 18 in place. The annular valve 18 is provided with air inlet ports 20 and with outlet ports 21 arranged in staggered relation to one another (see Fig. 3) in such a manner that by rotation of the annular valve the chambers 16 are 20 put into communication with the annular inlet passage 8 or with the annular outlet passage 10. By means of a toothed segment 22, a rack 23, a lever 24, an eccentric rod 25, and an eccentric 26 on the controlling 25 shaft 27 the rotary valve 18 is rotated back and forth in accordance with the cycle in the cylinder.

The drawing does not illustrate constructional details such as the manner in which 30 the annular valve 18 is guided and sealed with respect to the parts 5 and 12, because these details do not form part of the invention.

The annular part 5 has been shown integral with the cylinder wall 4, but it is obvious that these elements may be made as separate parts, for instance, as shown in Figs. 1^a and 1^b where the annular part of the cylinder head is shown composed of the 35 part 5, containing the inlet and outlet passages 8 and 10, and of an intermediate annulus 28 or 29. From this it will appear that the invention can be carried out in various ways, which while differing in construction all embody the gist of the invention.

What we claim is:—

1. In a four-stroke internal combustion engine, the combination with the working cylinder, of a cylinder head comprising an 50 annular part having a central aperture extending in the axis of said working cylinder, but of a smaller diameter than said working cylinder, and containing air-inlet and com-

bustion gases-outlet passages, a member provided within said annular part in coaxial 55 relation therewith, fuel supply means in said member, a plurality of valves carried by said member both for admitting air and discharging combustion gases, and a means for controlling said air-inlet and combustion 60 gases-outlet passages.

2. In a four-stroke internal combustion engine, the combination with the working cylinder, of a cylinder head comprising an annular part having a central aperture extending in the axis of said working cylinder, but of smaller diameter than said working cylinder and containing air-inlet and combustion gases-outlet passages, a member provided within said annular part and closing 65 said central aperture, fuel supply means in said member, a plurality of valves carried by said member both for admitting air and discharging the combustion gases, and a rotary valve between the said annular part 70 and said member for controlling said air-inlet and combustion gases-outlet passages.

3. The combination as set forth in claim 2, comprising a controlling shaft and means operated by said shaft for actuating said 80 rotary valve.

4. The combination as specified in claim 2, in which the parts provided in said rotary valve are arranged in staggered relation to each other and adapted to alternately communicate with said air-inlet and combustion 85 gases-outlet passages.

5. The combination as specified in claim 1, in which said annular part is made integral with the wall of said working cylinder.

6. The combination as set forth in claim 2, in which said valves are provided with valve stems, said combination comprising a ring connected with said valve stems and an 95 actuating mechanism for simultaneously opening and closing all the valves by means of said ring.

7. The combination as specified in claim 2, in which said member is provided with 100 valve chambers for said valves and cooling jackets for said valve chambers.

It testimony whereof we affix our signatures.

CORNELIS ZULVER.
GERARD JOHAN LUGT.
